JOINING LENGTHS OF METAL

Henry J. Sharp, Emsworth, Pa., assignor to Commonwealth Trust Company, trustee, Pittsburgh, Pa.

Application April 7, 1934, Serial No. 719,475

14 Claims. (Cl. 189—36)

This invention relates to the joining of lengths of metal pieces and especially to framing and the construction of frames formed of metal and is applicable to the manufacture of frames for picture, display card and bulletin board framing, and also to the manufacture of metal door frames and other like frame constructions, as well as other uses where lengths of metal are joined together, either at an angle or incline. 5
 Metal frames and other articles formed of extruded metal strips have heretofore been constructed, but considerable difficulty has been experienced in the forming of the joints or corners. Some metals can be successfully soldered, but 10 other metals, such as aluminum, cannot be satisfactorily soldered. Welding can be used in some instances, particularly where the metal is thereafter painted, so that the discoloration caused by the heat of welding is covered by the paint. 15
 This is not desirable, however, where the natural finish of the metal is to be maintained or where the metal is provided with some special surface treatment which is detrimentally affected by the heat of welding. The use of bolts is not desirable 20 because the heads of the bolts are difficult to conceal at the front of the frame. According to the present invention, there is provided a connector element of a harder character than the elements to be joined and which interlocks therewith to make a tight joint. Moreover according 25 to a preferred embodiment of the present invention, there is provided a metal framing strip which can be formed by extrusion and which is provided with continuous means extending along the back thereof for use in forming the joint whereby the strip can be cut at any point in its length and such longitudinally extending means is available for making the joint. 30
 The invention further contemplates the provision of a joint formed through the cooperation of such longitudinally extending means and separate metal connectors. The invention provides a method by means of which one constructing 35 a frame may buy lengths of strip, cut them to any desired size and secure them together in a firm and rigid manner without resorting to soldering, welding, or to the use of bolts. The invention may be readily understood by reference to the accompanying drawing, in which 40

Figure 1 represents a front view of a frame corner constructed in accordance with my invention, a part of the front of the frame being broken away to show a part of the fastening means for the corner; 45

Figure 2 represents a transverse vertical section in the plane of line II—II of Figure 1; 50

Figure 3 shows the same corner construction in rear elevation; 55

Figure 4 is a perspective view of one of the fastening members; 60

Figure 5 is a perspective view of another of the fastening members; 65

Figure 6 is a view similar to Figure 3 showing the application of my invention to the formation of corners which are less than 90°; 70

Figure 7 is a perspective view of the strip from which the frame shown in Figures 1, 3, and 6 is constructed; 75

Figure 8 is a view similar to Figure 3 of a slightly different arrangement for use with wider frame strips; 80

Figure 9 is a perspective view of a portion of the strip from which the corner of Figure 8 is formed; 85

Figure 10 is a perspective view of one of the connectors used in making the corner shown in Figure 8; and 90

Figure 11 is a perspective view, partly broken away, of a further modification. 95

Referring first to the construction shown in Figures 1 to 7, there is shown in Figure 7 an extruded metal strip which may be of indefinite length. It is provided with a face or border portion 2 and a side or flange portion 3. It may have any desired external contour, the various steps or ribs on the outer surface of the border portion shown in Figure 7 being provided for ornamentation. On the inner surface of the border or front portion of the frame strip is a channel 4 having one side formed of a longitudinally extending upstanding rib 5, this rib being relatively thin in cross section. The other side of the channel 4 is formed by an upstanding flange 6 having an overhanging lip portion 6a. The flange or side portion 3 of the strip is also in the form of a channel on the inner face of the strip, the channel being designated 7. One side of the channel 7 is formed by a flange 8 having an overhanging lip 8a, while the other side of the channel is formed by a portion of the border portion 2 of the strip. A small ledge 9 extends longitudinally along the inner surface of the portion 2 of the strip parallel with the rib 5 and opposite the lip 8a. This cross-sectional shape of the strip is the same so that the strip can be cut at any place in its length and present the same cross-sectional shape. For instance, assuming that a right angle corner is to be formed, the strip may be cut diagonally along the line A—A in Figure 7. 55

Another portion of the strip may be cut along the line B—B whereby the two mitred surfaces may be brought together as shown in Figure 1 to form a right angle corner.

- 5 For securing the pieces together, two fastening members are preferably employed. One of these is shown in Figure 4 and the other is shown in Figure 5. The fastening member in Figure 5 comprises a flat angle member 10 formed to a sharp right angle, or other angle in the event that the corner being constructed is not a right angle. The angle member has a width considerably in excess of its height so that it is very rigid. It is preferably provided with notches or other irregularities 11 in the outer edges of the two legs thereof. The other connecting member shown in Figure 4 is also an angle member 12. It is conveniently formed by bending a strip of metal to the proper angle, and its width is relatively slight as compared with its height. It may be termed an "upstanding angle" while the one shown in Figure 5 may be termed a "flat angle member". Small barbs are preferably formed on the edges of the two arms of the angle member. 15 These barbs are inclined away from the ends of the angle member toward the corner. They are designated by the numeral 13, and they may be conveniently formed by nicking the metal with a cold chisel or other suitable implement. In assembling the corner, one of the arms of the member 12 is forced to its full length into the channel 7 of one of the two meeting pieces. The barbs serve to increase the frictional engagement between the member 12 and the channel in which 20 it is received, to make it extremely difficult to pull the angle member out after it has once been driven in. The framing strips themselves are of a metal such as aluminum, which is relatively soft, while the connector member 12 is of a hard metal, such as steel, and the barbs 13 possess some resilience. When the hard metal connector is forced into the slot or recess provided for it in the main frame members, the teeth or barbs on the surface of the hard metal member will so 25 grip the body of the softer member as to make it very difficult to separate the members so joined. Likewise, the one leg of the angle member 10 is inserted in one of the channels 4 on the border portion of one of the meeting strips. The rib 5, 30 which is more or less ductile and which is of small cross section, is then peened over into the notches 11. This may be conveniently done through the use of a hammer and punch. As shown in Figure 3, the metal which is thus peened over or 35 punched into the notches 11 at points 14, forms keys which tightly interlock the member 10 against movement in the channel 4. When the two angle members 10 and 12 have thus been secured to one of the two meeting strips, the other 40 arms of the two angle members 10 and 12 are entered in the respective channels 4 and 7 of the other strip. When the meeting edges of the two pieces are brought together as shown in Figure 1, the barbs 13 serve to prevent the joint from 45 spreading, and the rib 5 of the second piece is then punched or peened in to interlocking engagement with the other arm of the angle member 10 and the joint is complete.

It will thus be seen that after the ends of the 50 strips have been mitred to the desired angle, a joint can be very easily and simply formed, and the joint having once been formed cannot, without excessive abuse, be separated or destroyed. The joint can be easily made without marring 55 the finish of the strip, and from the front of

the frame all of the fastening means are concealed. The labor cost for making a frame is reduced to a minimum, while the cost of extruding the strip is very little more than the cost of extruding framing strips as heretofore constructed. 5 The angle member 10 shown in Figure 5 has its maximum strength in one plane, i. e., the flat plane of the metal. It therefore serves to effectively resist strains tending to open or spread the joint. The connector member 12, on the other hand, has its maximum strength in a direction 10 at right angles to the plane of the maximum strength of the connector 10. It therefore serves to effectively prevent bending of the frame in a direction transverse to the plane of the frame. This keeps the frame flat. By positioning one 15 of the connecting members adjacent the outside of the corner and the other one relatively close to the inside of the corner, the corner is further reinforced against spreading, and the meeting ends of the two pieces are held in contact along 20 their entire length.

It is obvious that the connector members 10 and 12, in addition to being formed to right angles, may be formed to various other angles so that hexagonal, octagonal, triangular and other shape frames can be produced. This is illustrated in Figure 6 wherein 10a designates a connector corresponding to the connector 10 of Figure 5, but bent to a lesser angle than 90°. The numeral 12a designates a connector corresponding to connector 12, but bent to an angle corresponding to the angle of the member 10a.

As a modification which is sometimes better suited to frames of considerable width, the arrangement shown in Figures 8 and 9 may be employed. In Figure 9, the contour of the strip is shown. As mentioned in connection with Figure 7, the outer contour or ornamental ribs or steps, is not important. The strip has a border or face portion 15 corresponding to the portion 2 of 45 Figure 7, and a flange or side portion 16 corresponding to the part 3 of Figure 7. The side portion 16 is provided with an internal channel 17 having flanged edges, the cross-sectional shape of the side portion 16 corresponding to the cross- 50 sectional shape of the side portion 7 of Figure 7. Extending longitudinally along the inner surface of the frame or border portion 15, are two relatively thin upstanding flanges 18 and 19 between 55 which is a relatively wide channel 20. In forming the joint or corner, a connector 21, similar in all respects to the connector 12, has its arms entered into the channel portions 17 of the meeting members. A relatively wide flat angle piece or plate 22 is provided which may be laid into 60 the channel 20 after the meeting pieces have been joined by the member 21. The flat angle member 22 is provided along one, and preferably both, edges with a series of notches 23. After this member has been laid in the channel 20, the 65 flanges 18 and 19 may be punched or dented in so as to interlock with the notches or recesses 23. Such punched-in or mutilated portions of the flanges 18 and 19 are indicated at 24. By increasing the number of notches, by using a wider 70 corner plate and by providing two flanges which may be mutilated to interlock with the corner plate instead of one as shown in the first modification described, a stronger joint can be constructed. Moreover, this joint has the advantage 75

that the member 22 can be laid into the channel 20 after the meeting ends have been brought tightly together and held by the member 21, whereas in the construction shown in Figures 1 to 7, the overhanging flange or lip 6a prevents the angle member 10 from being laid into the channels 4 after the strips have been brought together.

In this modification also, the member 21 is at the outside of the joint, whereas the inner edge of the member 22 is preferably relatively close to the inside of the joint. The two connecting members in this form, as in the previous form, are disposed in planes which are at right angles to each other so as to stiffen the frame against distortion. The relatively wide plate 22 in this form of joint naturally has a greater resistance to bending in the direction of its width than does the relatively smaller connector of Figure 5. For this reason also, it may be preferred in use with frames of larger sizes.

In Figure 11, I have shown two members of like cross section joined together in end to end relation. The two parts which are connected are indicated as being of substantially circular cross section, and they are designated 30 and 31. They are formed of a relatively soft metal with a hollow interior, being tubular. They are connected by means of a connector member 32. The member 32 is formed of relatively harder metal. It is shown as being tubular and as having barbs about the periphery thereof, the barbs at opposite sides of the metal being sloped in different directions, both sets of barbs being pointed toward the middle of the connector. The connector is slotted longitudinally whereby it can be compressed to facilitate its insertion in the ends of the two members to be joined. It is resilient so that when it is released it tends to spring back to its normal diameter. The barbs on the harder member penetrate the softer metal, as previously described in connection with member 12. This type of joint with tubular elements has particular utility in connection with extruded hand rails, stair banisters, and the like.

While many of the joints herein specifically illustrated are right angle joints, it will be understood that the invention is not restricted to a right angle joint, but may have any other angle as illustrated, for instance, by Figure 9, and the term "mitred" as used in the appended claims is intended to include any angular joint, whether a 45° angle or not.

While I have illustrated my invention as applied to a frame of particular cross-sectional shape, it will be understood that this is merely by way of illustration. It will also be apparent that various changes and modifications may be made in the detailed construction and arrangement of parts within the contemplation of my invention and under the scope of the following claims.

I claim:

1. A framing construction comprising framing strips having mitred ends which abut, each strip having a border portion and a side portion, each of said portions having a longitudinally extending channel therein, a connector comprising a rigid angle member in each of said channels having the legs thereof received in the channels of the abutting strips, at least one side of one of the channels and one edge of one of the connectors having interlocking portions.

2. A framing construction comprising framing strips having mitred ends which abut, each strip

having a border portion with a channel on the under surface thereof, and a rigid angle member having its legs received in the channels of the abutting strips, the channel and the connector having interlocking engagement, said connector having notches in at least one edge thereof, one side of the channel of each strip being peened into said notches to effect such interlocking engagement.

3. A framing construction comprising framing strips having mitred ends which abut, each strip having a border portion with a channel on the under surface thereof, and a rigid angle member having its legs received in the channels of the abutting strips, the channel and the connector having interlocking engagement, said connector having notches in at least one edge thereof, one side of the channel of each strip being peened into said notches to effect such interlocking engagement, said strips also having side portions with channels on the inner surfaces thereof, and other angle members received in the channels of the side portions, the angle members in the side portions being perpendicular to said first named angle members.

4. A framing construction comprised of framing strips having mitred ends which abut, thereby forming a corner, each strip having a border portion and a side portion, each of said portions having a longitudinally extending channel therein, and a connector in each corner received in the channels of the abutting side portions, each corner having a connector therein received in the channel of the abutting border portions, the angle members of each corner being in planes which are perpendicular to each other, and means forming an interlocking engagement between the angle members in the channels of the border portions and the sides of such channels.

5. A framing construction comprised of framing strips having mitred ends which abut, thereby forming a corner, each strip having a border portion and a side portion, each of said portions having a longitudinally extending channel therein, and a connector in each corner received in the channels of the abutting side portions, each corner having a connector therein received in the channel of the abutting border portions, the angle members of each corner being in planes which are perpendicular to each other, and means forming an interlocking engagement between the angle members in the channels of the border portions and the sides of such channels, the angle members in the channels of the border portions having notches along at least one edge thereof, the side of the channel being bent into the notches to form such interlocking means.

6. A frame construction comprising framing strips having mitred ends which abut to form a corner, each strip having a border portion and a side portion, the border portion having a channel therein, the side portion having a channel therein, each corner having a connector received in the abutting channels of the side portions, each corner having an angle member in the channels of the abutting border portions, the last named angle member having notches in the edge thereof, at least one side of the channel having portions which extend into the notches to form an interlocking engagement between the angle member and the strips.

7. A frame construction comprising framing strips having mitred ends which abut to form a corner, each strip having a border portion and a side portion, the border portion having a chan-

nel therein, the side portion having a channel therein, each corner having a connector received in the abutting channels of the side portions, each corner having an angle member in the channels of the abutting border portions, the last named angle member having notches in the edge thereof, at least one side of the channel having portions which extend into the notches to form an interlocking engagement between the angle member and the strips, the angle members in the channels of the side portions having barbs for resisting removal from the channels in which they are received.

8. A frame comprising a plurality of framing strips of similar cross-sectional shape having a border portion and a side portion, the side portion having a continuous channel therein extending longitudinally thereof, the inner face of the border portion also being provided with a channel, and connector members entered into the registering channels of abutting ends, one connector at each joint having interlocking engagement with the walls of the channel with which it contacts.

9. A frame comprising a plurality of abutting lengths of strips, each strip having a border portion and a side portion, the side portion having a continuous channel therein extending longitudinally thereof, the inner face of the border portion also being provided with a continuous longitudinal channel, at least one side of said last named channels having a side wall comprising a rib of relatively thin cross-section capable of being distorted into inter-locking engagement with a connector, and two connectors at each joint between abutting ends, one connector being received in the registering channels of the side portions and the other connector being received in the registering channels in the border portions, said last connector having means along its edges for interlocking engagement with said rib.

10. A frame comprised of a plurality of lengths of strip having angular abutting ends, all of the strips being of similar cross-sectional shape and size, each strip having a border portion and having a longitudinally extending continuous channel on the under face thereof, one side of said channel comprising a relatively thin flange of metal spaced inwardly from the edges of the strip and capable of being distorted into cooperation with a connector member received in said channel without such distortion being visible from the exterior of the frame, and a connector in the channels of abutting strips having edge portions which are forced into engagement with said relatively thin flange-like side wall of the channel.

11. A frame comprised of a plurality of framing strips of similar cross-sectional shape and having angular ends which are in abutting rela-

tion, each strip having a border portion and having a continuous longitudinally extending channel on the under face thereof, said channel being spaced inwardly from the side edges of the strip and having its side walls comprised of relatively thin ribs of metal, and angular connectors received in the registering channels at each joint, said connectors having teeth thereon which have an interlocking engagement with the relatively thin walls of the channel, said interlocking engagement being effected through distortion of the side walls of the channel, the distortion of the side walls being invisible at the front of the frame.

12. A framing strip having a face or border portion terminating at its inner edge in a relatively thin edge portion and provided at its outer edge with a side portion, the inside face of the side portion having a longitudinally extending continuous channel therein, the side walls of said channel having overhanging flange portions, the inner face of the border portion also having a longitudinally extending continuous channel therein, said channel serving to receive connectors at any point where the strip is severed.

13. A frame comprising a plurality of angularly abutting framing strips of like cross section, said strips having registering face or border portions and registering outer side wall portions, the inner faces of the border portions having longitudinally extending channels therein, the inner faces of the side portions also having longitudinally extending channels therein, said last mentioned channels having overhanging flanges thereon, angular corner connectors fitted into the channels in the side wall portions and retained against displacement by the overhanging flanges on the sides of said channels, and angular connector members in the channels of the abutting border portions.

14. A frame comprising a plurality of angularly abutting framing strips of like cross section, said strips having registering face or border portions and registering outer side wall portions, the inner faces of the border portions having longitudinally extending channels therein, the inner faces of the side portions also having longitudinally extending channels therein, said last mentioned channels having overhanging flanges thereon, angular corner connectors fitted into the channels in the side wall portions and retained against displacement by the overhanging flanges on the sides of said channels, and angular connector members in the channels of the abutting border portions, said first connectors being substantially perpendicular to the plane of the face of the frame and the second angular connectors lying substantially parallel to the face of the frame.

HENRY J. SHARP. 60
